UNITED STATES PATENT OFFICE.

EMMIT G. LATTA, OF FRIENDSHIP, NEW YORK, ASSIGNOR TO THE POPE MANUFACTURING COMPANY, OF PORTLAND, MAINE.

VELOCIPED.

SPECIFICATION forming part of Letters Patent No. 377,566, dated February 7, 1888.

Application filed March 22, 1887. Serial No. 231,932. (No model.)

To all whom it may concern:

Be it known that I, EMMIT G. LATTA, of Friendship, in the county of Allegany and State of New York, have invented new and 5 useful Improvements in Velocipedes, of which the following is a specification.

This invention relates to a tandem tricycle having two front driving and steering wheels and a rear trailing wheel.

10 The object of my invention is to produce a machine in which the steering is easy and reliable, in which the driving-gear is less expensive and more serviceable than heretofore, and which is especially adapted for use by two 15 ladies.

My invention also relates to the construction of the front saddle and handle-bar, whereby these parts may be adjusted vertically either together or independently, as desired.

20 The invention consists of the improvements which will be hereinafter fully set forth, and pointed out in the claims.

In the accompanying drawings, consisting of two sheets, Figure 1 is a longitudinal sectional elevation of my improved tricycle. Fig. 25 2 is a sectional fragmentary top plan view thereof. Fig. 3 is a vertical cross-section in line $x-x$, Fig. 1. Fig. 4 is a vertical longitudinal section, on an enlarged scale, in line $y-y$, Fig. 2. Fig. 5 is a horizontal section in line $z-z$, Fig. 4. Fig. 6 is a horizontal section in line $w-w$, Fig. 4. Fig. 7 is a perspective view 30 of the head on which the steering-post is supported.

35 Like letters of reference refer to like parts in the several figures.

A A' represent the front driving and steering wheels; $a a'$, the separate axles of these wheels arranged in line with each other and 40 reaching with their inner ends nearly to the center of the machine.

$a^2 a^3$ represent sprocket-wheels secured to the inner ends of the axles $a a'$, which latter are preferably plugged up, as shown.

45 B represents the central longitudinal member of the main frame arranged below the axles $a a'$, and having its rear portion, b , extending upwardly in rear of the axles and supporting the rear saddle, C, the post c of which is adjustably secured in the frame portion b by a 50 clamp, c' .

D represents a cross-brace secured at its middle to the frame-bar B by a T-piece, d , and having its upwardly and outwardly extending arms provided at their outer ends with sleeves 55 d' d'' .

d' represents tubes which are secured in the sleeves d' , and in which the axles $a a'$ turn. If desired, suitable ball-bearings may be interposed between the tubes d' and the axles. 60

E represents the tube which supports the front saddle-post, f , and which is secured with its lower end to the T-piece d and extends upwardly in front of the axles $a a'$.

F is the front saddle attached to the upper 65 end of the post f .

G represents the reach which connects the trailing wheel G' with the main frame, and which is provided with an upwardly-extending front portion, g . The latter passes through 70 a tube, g' , which is secured to the main frame by a cross-fitting, g'' . The front portion, g , of the reach may turn directly in the tube g' , as shown; but, if desired, suitable ball-bearings may be interposed between the reach and the 75 tube g' to reduce the friction. The upper end of the tube g' is secured to a head, H, which extends forwardly to the front saddle-tube, E, and is provided with dependent ears h , to which the inner ends of the tubes d' are secured by brazing or otherwise. The head H is provided at its front end with a clamp, h' , 80 which holds the front saddle-post, f , in position.

I represents the rear handle-bar, and i the 85 rod to the upper end of which it is secured.

i' represents the tubular steering-post, in which the rod i is adjustably secured by a clamp, i' , so that the rod can be raised and lowered. The lower end of the post i' turns 90 on a stud, i'' , which is secured to the head H.

J represents a gear-segment secured to the lower end of the steering-post i' and turning therewith. J' is a similar gear-segment secured to the upper end of the front portion, 95 g , of the reach above the head H and meshing with the segment J. These segments are prevented from turning on the tubes to which they are attached by ribs or feathers brazed to said tubes and seated in grooves in the 100 wheels.

j represents a dust-cap secured to the head

H and covering the gear-segments J J'. This cap also prevents the steering-post from being raised when an upward pressure is applied to the handle-bar.

- 5 A turning movement of the handle-bar I is transmitted by the segment J to the segment J', which latter, being supported by the reach G and trailing wheel G', causes the driving-wheels A A' and the main frame to turn with 10 the handle-bar. The segment J is preferably made of smaller radius than the segment J', to give the rider the advantage of greater leverage and to overcome to a great extent the tendency of either of the driving-wheels to swerve 15 on striking an obstruction. The tube g' is preferably inclined backwardly to cause the trailing wheel to incline toward the center of the circle in turning, thereby lessening the tendency of the wheel to slip or buckle.
- 20 k represents the rear crank-shaft journaled in a bearing, k', which is attached to the lower portion of the tube g'.
- k² represents the cranks secured to the shaft k, and k³ k⁴ the pedals attached to said cranks.
- 25 k⁴ represents a sprocket-wheel secured to the shaft k, and k⁵ represents a drive-chain which connects the sprocket-wheel k⁴ with the sprocket-wheel a² on the axle a.
- 30 The reach G is carried under the shaft k low enough to clear the cranks when they stand backwardly and downwardly at an angle of about forty-five degrees; but as the reach never swings laterally far enough to strike the cranks when they are directly under the shaft it is 35 not necessary to locate the reach lower than shown in the drawings.

L represents the front handle-bar, of crescent or arc shape, and secured at its center rigidly to a clamp, l, which latter is in turn 40 secured with its front end to the front saddle-post by a clamping-bolt, l', while its rear end is provided with an opening in which the steering-post i' turns freely. The front saddle-post and the steering-post are arranged 45 parallel with each other, so that the steering-post can turn in the clamp l in all positions of the latter. Upon loosening the clamp h' at the front end of the head H the front saddle and the front handle-bar can be raised and lowered 50 together. Upon loosening the clamp l the front handle-bar can be raised and lowered without disturbing the front saddle. By thus connecting the front saddle-post with the steering-post each of these posts supports the other 55 and both posts can be made lighter than if they were disconnected.

The head H is preferably constructed by forging, and is brazed to the upper end of the tube g'. The front portion of the head H is 60 brazed to the upper end of the tube E and terminated with the clamp h', which embraces the front saddle-post, f.

m represents a brace connecting the rear portion of the longitudinal member B of the 65 main frame with the lower end of the tube g'. By arranging the frame and steering-gear as

described a lady can conveniently occupy the rear seat.

n represents the front crank-shaft journaled in a bearing, n', which is adjustably attached 70 to the horizontal member B by a clamp, n².

n³ represents the cranks attached to the shaft n, n⁴ the pedals, n⁵ the sprocket-wheel, and n⁶ the drive-chain connecting the sprocket-wheel n⁵ with the sprocket-wheel a³ on the 75 axle a'.

Each rider drives one of the wheels A A' independent of the other rider, whereby the expense, weight, and friction of a balance or differential driving-gear are saved. After a little 80 practice the riders will drive the machine as well as if it had a balance-gear, and in some respects better, as they will readily learn to apply extra power to either wheel when it strikes an obstruction, thereby reducing the 85 strain on the frame and steering-gear, and will also learn to do a great part of the steering by varying the speed of the wheels, which is of great importance when the machine tilts forward so that the rear wheel does not touch 90 the ground. If either rider does less than half the work it is easily detected by the steering. The shortness of the axles permits the same to be made comparatively light without danger of springing.

O represents a small caster-wheel attached to the front end of the member B of the main frame for preventing the machine from tipping forward too far.

I claim as my invention—

1. In a tricycle, the combination, with the main frame, driving-wheels attached to the main frame, and a saddle-support attached to the main frame and arranged behind the centers of the driving-wheels, of a steering-post arranged above said frame and pivoted with its lower end thereto, a reach arranged below said frame and saddle-support, and pivoted with its upper end to the main frame, and connecting-gear, whereby the reach and the steering-post are connected, and whereby the reach can be turned on its pivot without moving the saddle, substantially as set forth.

2. In a tricycle, the combination, with the main frame and the driving-wheels attached thereto, of a saddle-post secured to the main frame, a trailing wheel, a depressed reach extending forwardly from the trailing wheel and pivoted to the main frame in front of said saddle-post, and a driving-gear attached to 110 the main frame above the depressed reach, substantially as set forth.

3. In a tricycle, the combination, with the main frame and the driving-wheels attached thereto, of a trailing wheel, a depressed bent 115 reach extending forwardly from the trailing wheel and provided with an upwardly-extending front portion, and a socket formed on the main frame for the reception of the front portion of the reach, substantially as set forth.

4. In a tricycle, the combination, with a main frame and driving-wheels having their

130

axles arranged above the main frame, of a trailing wheel, a reach connecting the trailing wheel with the main frame, and a saddle-support secured to the main frame below the centers of the driving-wheels and above the reach, substantially as set forth.

5 5. In a tricycle, the combination, with the main frame and two driving-wheels attached thereto, of a trailing wheel and a reach connecting the trailing wheel with the main frame by an inclined pivot at its front end, whereby the trailing wheel is caused to incline toward the center of the circle in turning, substantially as set forth.

10 6. In a tricycle, the combination, with the main frame provided with a tube, g' , and a seat-support, b , secured thereto, of a trailing wheel, and a reach, G , provided with an upwardly-extending front portion, g , seated in 20 the tube g' , substantially as set forth.

15 7. The combination, in a velocipede, of the longitudinal member B of the main frame, a cross-brace, D , secured thereto below the center of the wheels and provided with exterior 25 axle-supports, and a head, H , secured to the main frame and provided with interior axle-supports, substantially as set forth.

20 8. The combination, with the main frame, of the head H , cross-brace D , and tubes d^2 , 30 secured to the head H and the cross-brace D , substantially as set forth.

9. The combination, in a tandem tricycle, of a saddle-post, a steering-post arranged parallel with the saddle-post, and a connecting-piece secured to the saddle-post and provided with a bearing in which the steering-post turns, substantially as set forth. 35

10. The combination, with the saddle-post f and the steering-post i' , of the clamp l , adjustably secured to the saddle-post and provided with an opening in which the steering-post turns, substantially as set forth. 40

11. The combination, in a tandem tricycle, of a front saddle-post and a front handle-bar adjustably secured to the saddle-post, whereby 45 the front handle-bar can be raised and lowered with the saddle-post or independently thereof, substantially as set forth.

12. In a tandem tricycle, the combination, with the front saddle-post and the steering-post, of an adjustable clamp connecting the saddle-post with the steering-post, and a front handle-bar secured to said clamp, substantially as set forth. 50

Witness my hand this 9th day of March, 55
1887.
